UNITED STATES PATENT OFFICE.

NATHANIEL M. LOWE, OF BOSTON, MASSACHUSETTS, ASSIGNOR TO HIMSELF,
FRANK P. STONE, AND CHARLES A. SHAW, OF SAME PLACE.

COIN-OPERATED PLATFORM WEIGHING-SCALE.

SPECIFICATION forming part of Letters Patent No. 449,626, dated March 31, 1891.

Application filed May 22, 1890. Serial No. 352,779. (No model.)

To all whom it may concern:

Be it known that I, NATHANIEL M. LOWE, of Boston, in the county of Suffolk, State of Massachusetts, have invented certain new and useful Improvements in Coin-Operated Platform Weighing-Scales, of which the following is a description sufficiently full, clear, and exact to enable any person skilled in the art or science to which said invention appertains to make and use the same, reference being had to the accompanying drawings, forming part of this specification, in which—

Figure 1 is a front elevation showing my improvement, the dial being removed and the body of the case being broken away; Fig. 2, a like view showing the position of the parts when in use; Fig. 3, a vertical section of the governor; Fig. 4, a horizontal section of the same, and Fig. 5 a view illustrating certain details of construction.

Like letters and figures of reference indicate corresponding parts in the different figures of the drawings.

My invention relates more especially to providing platform weighing-scales of this class with controlling mechanism for preventing the jarring or vibratory movements of certain parts of the weighing and indicating mechanism resulting from the sudden expansion and contraction of the scale-spring or balance-spring when weight is improperly applied and removed from the scale-platform; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the case, which may be of any suitable form and construction, and is provided with a platform at its lower end in the usual manner. The case is provided with a dial having an index-finger b. The balance-spring d has one end secured to a rod f, vertically adjustable in a lug g on said case. The lower end of the spring is se-

cured to a plate h, connected by a rod i with the scale-platform, said plate being herein-after denominated the "balance-spring" plate. The finger b is journaled in a bracket j in the case, and its arbor k bears a pinion m, which meshes with a vertical gravitational rack or measuring-rod p, said rack being fitted to slide in the bracket j, and having its lower end resting on the balance-spring plate h.

A coin-chute q opens through the top of the case. A vertical lever r is pivoted to the lower end of said chute and an adjusting-screw t passes through one arm of said lever into engagement with the chute-wall. In the upper arm of said lever a retaining pawl or click v is pivoted in position to engage upwardly-beveled teeth w on the outer edge of the rack p, and throw the lower end of said lever outward when the rack returns after having descended, as hereinafter described. A forked gravity-lever 15 is pivoted astride the lower end of the chute opposite the lever r, and is provided with adjusting-weights 16. A horizontal rod 17 is pivoted by one end to the lower end of the lever 15, the free end of said rod sliding through the bracket j and engaging downwardly-beveled teeth 18 on the rack p. This locks the rack and prevents it from actuating the index when weight is applied to the platform until the lever 15 is thrown outward by a coin in the chute. Said lever is adjusted by means of the weights 16, so that a coin of a determined weight is required to move it sufficiently to free the rack. The lever r is designed to resist the weight of the coin, and said levers r and 15 are so constructed and arranged that the coin will be held between them until the lower end of the lever r is thrown outward, as hereinafter described.

A rectangular tank B is disposed within the case adjacent to the spring d. Vertically-arranged fins or plates 20 project inward from the walls of the tank to prevent the liquid therein from rotating too freely. A vertically-arranged spirally fluted or threaded shaft C is mounted in steps 21 and 22, respectively, secured within the case and centrally on the bottom of the tank. Vertical

floats or paddles 23 are arranged radially around and secured to the lower end of the shaft within the tank. The tank is filled with liquid, preferably water, in which said paddles work, and is provided with a cover 24. An interiorly threaded or fluted nut 25 is fitted to travel on the threaded portion of the shaft C. A vertical standard 27 is secured at its lower end to the spring-plate h and a lever 26 is pivoted to the upper end of this standard. The short arm of said lever is provided with a fork 29, (see Fig. 5,) which is pivoted to the nut 25. The opposite end of this lever is provided with a counter-weight 28.

15 In the use of my improvement, the parts being in the position shown in Fig. 1, when weight is applied to the platform, the connecting-rod i draws the plate h downward. The rack p is prevented from falling by the locking-rod 17. A coin 30 being inserted in the coin-chute falls against the gravity-lever 15, throwing it outward sufficiently to withdraw the locking-rod from engagement with the rack. The rack or measuring-rod p then falling until it meets the balance spring-plate h actuates the index finger b or moves it forward a corresponding distance, thereby indicating the weight on the dial. As the rack descends, the pawl v slips over the teeth w and does not affect the lever r. When the platform is relieved from the weight, the spring d contracts and carries the plate h upward, elevating the rack again. The teeth w thereon engaging the pawl v throw the lower end of the lever r outward and release the coin, which falls from between the levers r and 15, into a suitable receptacle. The weights 16 now cause the lever 15 to fall inward again, and the locking-rod 17 engaging the rack-teeth 18 locks said rack until again released by a coin.

45 In machines of this class as ordinarily constructed when the weight is suddenly applied to and removed from the scale-platform, the force of the spring d, acting upon the rack, causes the parts to vibrate violently, thereby frequently disarranging or breaking the rack locking and indicating mechanism—as, for instance, would be occasioned by a person jumping up and down while standing on the scale-platform. In my improvement this objection is overcome. As the balance-spring plate h descends, the standard 27 draws the lever 26 downward, causing the nut 25 to travel on and rotate the spirally fluted or threaded shaft C. The paddles or floats 23 on said shaft working in the liquid in the tank B serve to check or retard the descent of the balance-spring plate h. 55 As said plate is drawn upward by the spring the paddles rotated again by the nut render such ascent gradual and prevent all harmful jar or vibration of the parts.

60 I do not confine myself to the use of any special number of paddles or floats 23 on the

spirally fluted or threaded shaft, as one or more may be employed. Neither do I confine myself to the use of a rectangular tank B, as a tank of any suitable form with or without the fins 20 may be employed; nor to arranging the float or paddle-shaft vertically, as it may be arranged horizontally by introducing proper intermediate connecting mechanism between the paddle-shaft and platform-rod i; nor to placing the tank in any special position in the case of the scale, as it may be located in any convenient position to enable the platform mechanism to be connected with the paddle-shaft in such a manner as to produce rotary movements of the shaft when the scale-platform falls and rises in the act of weighing; nor to pivoting the rod or standard 27 to the balance-spring plate h.

Having thus explained my invention, what I claim is—

1. In a coin-operated weighing-scale, the combination of a tank for containing a liquid, a helically-fluted shaft extending into said tank, a paddle or paddles disposed in said tank on said shaft, a nut fitted to work on said shaft, and mechanism connecting said nut with the scale, whereby the paddle-shaft is rotated during the weighing operation, substantially as described.

2. In a coin-operated weighing-scale, the combination of a tank for containing a liquid, a helically-fluted shaft extending into said tank, a paddle or paddles disposed in said tank on said shaft, a nut fitted to work on said shaft, a lever connected with said nut, a standard onto which said lever is pivoted, and a balance-spring plate supporting said standard and connected with the weighing mechanism, substantially as described.

3. In a coin-operated scale, the combination of a vertically-movable rack connected with the weighing mechanism and provided on its inner face with plain teeth and on its outer face near its upper end with upwardly-inclined teeth and near its lower end with downwardly-inclined teeth, an index-finger engaged by said plain teeth, a coin-chute, a gravity-lever pivoted at the discharge of said chute, a rod pivoted to said lever and adapted to engage said downwardly-inclined teeth for locking the rack, a coin-lever pivoted to said chute and projecting into the path of the coin, and a pawl on the upper arm of said lever in position to be engaged by said upwardly-inclined teeth on the ascent of the rack, substantially as described.

4. The combination of the case A, gravity-rack p, the chute q, weighted lever 15, rod 17, and lever r, provided with the pawl v, substantially as described.

5. The combination of the case A, balance-spring d, rack p, the standard 27, the lever 26, pivoted thereto, the tank B, the helically-fluted shaft C, provided with paddles

23, and the nut 25 on said shaft and connected to said lever, substantially as described.

6. A rack-locking device for the index-rack of a coin-operated weighing-scale, comprising the index-rack, two levers pivoted to the coin-chute and adapted to support the coin, one of said levers having a determined gravity-

force and being provided with a pivoted arm for locking said rack, and the companion lever provided with a pawl engaging teeth on said rack, substantially as described.
